UNITED STATES PATENT OFFICE.

ERNEST DISINGER, OF CLEVELAND, OHIO, ASSIGNOR TO WILLARD STORAGE BATTERY COMPANY, OF CLEVELAND, OHIO, A CORPORATION OF WEST VIRGINIA.

CASTING-MACHINE.

1,354,732.

Specification of Letters Patent.

Patented Oct. 5, 1920.

Application filed July 11, 1916. Serial No. 108,563.

To all whom it may concern:

Be it known that I, ERNEST DISINGER, a citizen of the United States, residing at Cleveland, in the county of Cuyahoga and 5 State of Ohio, have invented a certain new and useful Improvement in Casting-Machines, of which the following is a full, clear, and exact description.

This invention relates to a casting machine such as may be employed advantageously in casting lead storage battery grids.

One of the objects of the invention is to provide a machine which is efficient, particularly as to the amount of heat required 15 to bring the molten lead up to the desired high temperature for casting the grids.

A further object is to provide a casting machine wherein all the different operations which include the shifting of the molds up 20 to pouring position, the opening, closing, locking and unlocking of the molds, the control of the valves, and the tilting of the ladle to which molten metal is allowed to run by the operation of the valves, are performed automatically and in certain predetermined timed relationship, so that the 25 grids may be cast not only rapidly, but efficiently.

In the attainment of the first of the above- 30 mentioned objects, I employ in addition to the usual melting furnace in which the metal is brought to a molten state, a secondary heating receptacle in the form of a ladle, which receives from the melting furnace a 35 predetermined amount of molten metal, or an amount sufficient to cast a grid, and is heated so as to raise this amount of metal to the required temperature for effective casting and is then tilted to cause the metal 40 to be poured into the mold. Thus there is avoided the necessity of heating a large amount of metal to the temperature required for casting.

In the preferred embodiment of my invention, a series of molds are arranged on the periphery of a turn-table or revolving platform, each mold being composed of relatively movable parts with which are associated opening and closing, and locking and 45 unlocking devices. This turn-table which is arranged in proximity to the ladle referred to above and is designed to bring the molds, one at a time, up to pouring position, has associated with it mechanism for moving 50 the turn-table step by step, for closing and

opening, and for locking or unlocking the molds, for tilting the ladle and for operating the valves which control the flow of molten metal from the furnace or primary heating receptacle to the ladle or secondary heating receptacle, so that there is eliminated practically all hand labor except that required to lift the cast grids from the molds.

My invention may be further briefly summarized as consisting in certain novel details of construction, and combinations and arrangements of parts which will be described in the specification and set forth in the appended claims.

In the accompanying sheets of drawings, Figure 1 is a top plan view of the casting machine, certain portions being broken away and omitted; Fig. 2 is a side view of the same; Fig. 3 is a vertical sectional view 75 substantially along the line 3—3 of Fig. 1, looking in the direction indicated by the arrows; Fig. 4 is a horizontal sectional view substantially along the line 4—4 of Fig. 3; Fig. 5 is a horizontal sectional view through 80 a portion of the machine substantially along the line 5—5 of Fig. 3, looking in the direction indicated by the arrows; Figs. 6 and 7 are respectively a plan and sectional view showing details of the mechanism for shifting the turn-table; Figs. 8 and 9 are respectively a side view and a sectional view showing details of the valve controlling mechanism; Fig. 10 is a plan view of the valve 85 controlling mechanism showing the construction more in detail than in Fig. 1; Fig. 11 is a view partly in side elevation and partly in section, showing particularly the mold closing and opening, and locking and unlocking mechanism; Fig. 12 is a detail 90 view showing in elevation a portion of the ladle-tilting mechanism; Fig. 13 is a top plan view of one of the molds showing also a portion of the locking and unlocking mechanism; Fig. 14 is a side view of a portion 95 of the locking and unlocking mechanism for the mold; Fig. 15 is a transverse sectional view through the combined pouring ladle and secondary heating receptacle; and Fig. 16 is a detail sectional view illustrating the manner in which the upper stationary part of the central cylinder is supported by the lower part.

The machine constituting the subject matter of this invention may be constructed in 110

numerous forms, and the details of arrangement and also of construction of the operating mechanism may be modified considerably from the arrangement and details shown, and while in the drawings I have shown only one construction, I wish it to be understood that the construction shown is merely illustrative of one embodiment of the invention, and that I am not to be limited thereto. In the embodiment illustrated in the drawings, the machine includes a circular base 10, centrally from which there extends a hollow, cylindrical standard or column 11, flanged at its upper end, as shown at 12, and supporting through the medium of rollers or ball-bearings 13, a rotary turn-table or platform 14. This turn-table which is in the form of an annulus carries a plurality of molds 15, each preferably composed of two parts 15^a and 15^b which are supported respectively by a pair of holders or jaws 16 and 16^a. The jaw 16^a of each mold is preferably stationary being mounted directly on the revolving platform, while the outer jaw 16 is pivotally mounted on a pin 17, carried by a bracket 18, on the under side of the turn-table, and just beyond the flanged periphery of the standard or column 11. The manner in which the movable part of the mold, or movable jaw, is supported and is adapted to be shifted is perhaps best illustrated in Fig. 11. By referring particularly to Figs. 2 and 11, it will be seen that the jaw 16 of each mold extends downwardly beneath the platform where it is pivoted on pin 17 and is provided with an arm 19, extending downwardly below the pivot pin 17, this arm being provided at its lower end with a roller 20, which is designed to engage the periphery of a cam 21, which controls the opening and closing of the molds. This cam 21 is near the bottom of the machine, and is formed as a flange on the base 10.

The turn-table may be moved step by step to bring the molds successively to the pouring ladle, by many different forms of shifting devices, but in the drawings I have shown a simple mechanism which includes a pneumatic cylinder or other suitable fluid pressure double-acting motor cylinder 22, containing a piston (not shown) connected to a plunger 23, pivotally connected at its forward end to a link 24 (see Fig. 4), which at its forward end is pivotally connected to a lever 25 (see Fig. 3) which is secured to the lower end of a vertical shaft 26, supported in hubs or bosses 27 at the center of the column 11. This shaft has secured to its upper end, an operating arm or lever 28, provided at its outer end with a pivoted spring-pressed pawl 29, designed to engage rack teeth 30, formed on or secured to the turn-table 14. With this mechanism, by one stroke of the piston or plunger 23, the turn-table is moved through an arc of a

circle sufficient in extent to bring the mold from one position to the next. In this case, as will be seen from Fig. 1, the turn-table is provided with six molds, so that at each stroke of the piston, the turn-table will make 7 one-sixth of a revolution.

By this step-by-step movement, the molds are brought successively to pouring position, which is just beneath a combined pouring ladle and secondary heating receptacle 7 31, which is pivotally supported to turn about a horizontal axis in a suitable frame 32. The heating medium, which is preferably in the form of a gas which will produce a hot flame, is preferably admitted through 80 a pipe 33, constituting one of the trunnion supports for the ladle, the ladle being preferably provided with a heating chamber 37^a in its lower portion as shown in Fig. 15.

This ladle is designed to receive metal 85 from a suitable spout 34, which in turn is connected by a pipe 35, to the melting furnace 36, in which is supplied the metal to be melted. This melting furnace, which may be of any suitable construction, is not 90 shown in detail.

Between the spout 34 and the melting furnace 36, is at least one, and preferably, two valves 37 and 38, which are automatically operated, and control the flow of metal from the melting furnace to the ladle. These valves are preferably operated in sequence, the valve 37 first being opened to admit molten metal into the section of the pipe 35, between the two valves, and then this valve 100 is closed, and the forward valve 38 is opened to permit the predetermined amount of metal which has been admitted to the pipe, to pass into spout 34, and thence into the ladle 31. As here shown, the valve stems are provided with laterally projecting arms 39 and 40, which are operated by rods 41 and 42, which are connected together as best shown in Fig. 9, and are provided with lost motion connections with the arms 39 and 40 to prevent 110 binding. The rod 42 extends forwardly to near the center of the turn-table, where it is connected to an arm or lever 43, secured to the upper end of a vertical shaft 44, mounted for rotary movement in a stationary vertical support 45, which at its lower end is provided with a pinion 46, adapted to be rocked back and forth by a gear segment 47 at the inner end of arm 28 which is oscillated by the motor to turn the turn-table step by 120 step.

For the purpose of tilting the ladle, an upright arm 48 is provided and arranged in the path of movement of the oscillating arm 28, which turns the turn-table and actuates the valves. This arm, which is illustrated perhaps most clearly in Figs. 2 and 3, is pivoted at its lower end at 48^a, and extends upwardly from a point below the arm 28 above the same, where it is connected to a rather 130

long rod 49, extending past the ladle toward the furnace. The outer end of this rod 49 is provided with rack teeth 50 (see particularly Fig. 12) which are adapted to engage a pinion 51, provided on the trunnion pipe 33. As will be explained more fully subsequently, on the forward stroke of the arm or lever 28, the ladle is restored to normal position by a spring 52, which pulls the rod forwardly and on the return stroke of the arm or lever 28, the rod is pulled in the reverse direction by the engagement therewith of the arm 28, and during this movement the ladle is tilted so as to pour the metal into the mold.

It has been previously stated that by the engagement of the roller 20, carried by the depending arm 19 of the movable mold section or jaw, with the cam 21 which is provided near the base of the machine, the molds are adapted to be opened and closed. This cam is so designed that it will cause the closure of each mold just before it reaches pouring position, and will cause the opening of the mold after it has been moved a suitable distance away from, or beyond pouring position, or a sufficient length of time after the pouring, to enable the metal to congeal or harden, and to permit the cast grid to be removed from the mold. I have discovered that in order that effective results may be obtained, particularly when the machine is employed for casting storage battery grids, it is desirable to provide in addition to the opening and closing mechanism, means for locking and unlocking, and also tightly squeezing the mold sections together. This mechanism is embodied in the present machine, and in the form of the invention here shown, it comprises a pair of pivoted locking levers 54, arranged at the ends of each mold, these levers being pivotally supported on the stationary jaw or mold supporting member 16^a, and at their outer or free ends being provided with hook-like members 54^a, which are adapted to engage over lugs 55, carried by the movable jaw or support 16 for the movable mold section. Acting in conjunction with these two locking levers 54 of each mold, is a yoke 56, which extends part way around the stationary jaw 16^a and is pivotally supported from the ends of the jaw 16^a by pins 57. This yoke is provided with an inwardly extending arm 58, provided with a roller 59, which engages a cam 60 on a stationary cylinder 61, which extends upwardly above the movable platform as shown particularly in Figs. 2 and 3, and may be supported from the upper end of the column 11 by brackets 62 (see Figs. 5 and 16) this cam being so shaped that it successively elevates and lowers the inner end of the yoke. The forward ends of the yoke adjacent the rear ends of the locking arms or levers 54, are provided with

lugs 63, adapted to engage the locking arms or levers 54, forwardly of their pivotal points, so as to depress these locking levers when the inner end of the yoke is elevated, and they are provided also with lugs 64, 70 which engage the locking levers 54 rearwardly or inwardly of their pivotal points, so as to elevate the same when the inner end of the yoke is lowered, so that the noses or hooked ends of the locking levers will be 75 swung into, or out of locking engagement with the lugs 55. In order that the mold sections may be very tightly squeezed together the pins 57 which pivotally support the yoke 56, are provided with eccentric portions 57^a, on which the rear or inner ends of the locking levers are loosely pivotally supported. These eccentric portions 57^a are so arranged that just after the locking levers engage over the lugs 55, the eccentric pins, 85 which are secured to the arms of the yoke so as to move therewith, pull the arms 54 inwardly, causing very tight engagement between the locking levers 54 and the lugs 55, and squeezing the mold sections together 90 very tightly.

The operation of the machine above described, is as follows: On the forward stroke of the operating arm or lever 28, the turn-table is moved one step, or through one-sixth 95 of a revolution, bringing an empty mold, which is now closed and locked, to pouring position, and moving beyond pouring position, the mold into which the metal had just previously been poured. Simultaneously 100 with this movement of the turn-table and molds, the ladle is restored to normal position by means of the spring 52, which pulls the rod 49 forwardly, and valve 37 is closed, and valve 38 opened so as to permit a predetermined quantity of the molten metal to pass 105 from the pipe 35 into the ladle 31, this being accomplished through the parts 39, 40, 41, 42, 43, 44 and 45. As soon as the metal is received in the ladle, its temperature is 110 quickly raised to the point where it is suitable for casting. As the amount of metal in the ladle is small compared with that in the furnace, or primary heating receptacle, only an exceedingly short interval of time and a 115 small amount of heat is required to raise the metal to the desired temperature for casting.

On the return stroke of the operating lever 28, the ladle is tilted and the metal therein is poured into the mold beneath, this 120 tilting of the ladle being due to the engagement of the arm 28 with the upright ladle tilting lever 48. Simultaneously with this tilting of the ladle, the valve 38 is closed and the valve 37 is opened so as to permit a 125 fresh quantity of the molten metal to be drawn from the furnace into the pipe 35, between the two valves.

Then, again, on the next forward stroke of the lever 28 an empty mold is brought 130

up to pouring position and the mold into which the metal has just been poured is moved from pouring position. The mold remains closed after it leaves pouring position 5 for a part of a revolution of the table, or until the metal has cooled and hardened sufficiently to enable the cast grid to be removed; then the mold is automatically unlocked by reason of the swinging of the yoke 10 56 by the cam slot 60, and immediately after the mold is unlocked, it is opened by the inward swinging of the arm 19, as the roller 20, at the lower end of the arm 19, follows the contour of the cam 21, the latter 15 being so shaped as to cause the opening of the mold when the latter reaches a certain position. The mold then remains open while the turn-table is moving through a certain predetermined portion of a revolution, and 20 during this time the grid will be removed, and just before the mold has again been brought to pouring position, it is closed by the action of the cam 21 on the roller 20, and is immediately after locked in the manner 25 previously described, and then the mold sections are squeezed together by the action of the cam 60 on the yoke 56, which in turn controls the locking levers or arms 54.

In this manner the grids are cast rapidly, 30 and much of the hand labor is eliminated, but at the same time the grids are practically all well formed, and the percentage of defective grids is reduced to a minimum. Additionally, there is a decided gain in efficiency over the old methods of casting, for 35 the reason that it is not necessary to heat the entire mass of molten metal up to the temperature which is required for casting, only so much of the metal being brought to 40 casting temperature as is required to cast a grid.

As previously stated, my invention in its broad aspects may be carried out in ways other than here shown, and I aim in my 45 claims to cover all modifications which do not involve a departure from the spirit of my invention.

Having thus described my invention, what I claim is:

50 1. In casting apparatus, a primary heating receptacle or furnace in which metal is adapted to be melted; a secondary heating receptacle adapted to receive molten metal from the first-named receptacle, and to raise 55 the temperature of the molten metal to a point suitable for casting; and means between the first and second receptacles for causing a predetermined amount of molten metal to be drawn from the first receptacle 60 into the second.

2. In casting apparatus, a primary heating receptacle or furnace in which metal is adapted to be melted; a secondary heating receptacle adapted to receive molten metal 65 from the first-named receptacle, and to raise

the temperature of the molten metal to a point suitable for casting; and a valved pipe between the first receptacle and the second for transmitting predetermined amounts of molten metal from the first to 70 the second receptacle.

3. In casting apparatus, a primary heating receptacle or furnace in which metal is adapted to be melted; a secondary heating receptacle adapted to receive molten metal 75 from the first-named receptacle, and to raise the temperature of the molten metal to a point suitable for casting; a pipe between the first receptacle and the second, and two spaced valves in said pipe adapted to be 80 operated consecutively.

4. In casting apparatus, a primary heating receptacle or furnace in which metal is adapted to be melted; and a secondary heating receptacle adapted to receive molten 85 metal from the first-named receptacle, and to heat the molten metal to a temperature suitable for casting, said second receptacle being in the form of a tiltable pouring ladle and means for conveying molten metal from 90 the first-named receptacle to the second receptacle.

5. In casting apparatus, a heating receptacle, a delivery receptacle adapted to receive metal from the heating receptacle, a 95 traveling mold conveyer, means for shifting said conveyer so as to bring the molds successively to pouring position adjacent the delivery receptacle, and means operating in predetermined timed relationship with the 100 conveyer shifting means for causing the delivery of a predetermined amount of metal from the heating receptacle into the delivery receptacle at each movement of the conveyer.

6. In casting apparatus, a heating receptacle, a delivery receptacle adapted to receive metal from the heating receptacle, a traveling mold conveyer, means for shifting said conveyer so as to bring the molds successively to pouring position adjacent the 110 delivery receptacle, and means operating in predetermined timed relationship with the conveyer shifting means for causing in sequence the delivery of a predetermined amount of metal from the heating receptacle to the delivery receptacle, and the delivery of a predetermined amount of metal from the delivery receptacle into a mold. 115

7. In casting apparatus, a primary heating receptacle; a secondary heating receptacle adapted to receive metal from the first; a traveling mold conveyer; mechanism for shifting said conveyer so as to bring the molds successively to pouring position adjacent the secondary heating receptacle, and 120 for tilting the secondary receptacle; and means for causing a predetermined amount of metal to be delivered from the primary receptacle into the secondary receptacle at 125 each movement of the conveyer.

8. In casting apparatus, a mold conveyer; a plurality of molds carried thereby, each composed of relatively movable parts so that the molds may be closed and opened; and a mechanism for closing and opening the molds, for locking and unlocking the relatively movable parts, and coöoperating devices carried by and individual to each mold for squeezing the relatively movable sections together when the mold is closed.

9. In casting apparatus, a mold conveyer provided with a plurality of molds, a melting furnace, a pouring ladle, means for delivering molten metal from the furnace to the ladle, and related means operating in predetermined timed relationship for shifting the conveyer and for tilting the ladle so as to cause molten metal to be poured from the ladle into a mold.

10. In casting apparatus, a mold conveyer provided with a plurality of molds; a pouring ladle adapted to be supplied with molten metal; and mechanism for shifting the conveyer step by step, for tilting the ladle, and for opening and closing the molds.

11. In casting apparatus, a mold conveyer provided with a plurality of molds; a pouring ladle adapted to be supplied with molten metal; mechanism for shifting the conveyer step by step, for tilting the ladle, and for opening and closing the molds; and means for supplying molten metal to the ladle.

12. In casting apparatus, a mold conveyer provided with a plurality of molds; a pouring ladle adapted to be supplied with molten metal; mechanism for shifting the conveyer step by step, for tilting the ladle, and for opening and closing the molds; and means for supplying a measured or predetermined quantity of molten metal to the ladle.

13. In casting apparatus, a mold conveyer provided with a plurality of molds; a pouring ladle adapted to be supplied with molten metal; mechanism for shifting the conveyer step by step, for tilting the ladle, and for opening and closing the molds; and means for supplying a measured or predetermined quantity of molten metal to the ladle, said ladle being in the form of a heating receptacle.

14. In casting apparatus, a melting furnace; a tiltable pouring ladle; means for supplying molten metal from the melting

furnace to the ladle; a traveling conveyer for a plurality of molds; and means for moving the conveyer step by step, so as to bring the molds successively to the ladle and for tilting the ladle in predetermined timed relationship.

15. In casting apparatus, a melting furnace; a tiltable ladle; means for delivering molten metal from the furnace to the ladle, including a valved pipe between the furnace and ladle; a conveyer for a plurality of molds, adapted to bring the molds successively to the ladle, and means operating in predetermined timed relationship for causing the conveyer to be shifted and for causing molten metal to be delivered from the receptacle to the ladle at regular intervals.

16. In casting apparatus, a melting furnace; a tiltable ladle; means for delivering molten metal from the furnace to the ladle including a valved pipe between the furnace and ladle; a movable conveyer for a plurality of molds; and means for shifting the conveyer, for tilting the ladle, and for opening and closing the valved pipe.

17. In casting apparatus, a melting furnace; a tiltable ladle; a valved pipe between the furnace and ladle; a conveyer; a plurality of molds on the conveyer, and composed of relatively movable parts so as to permit the molds to be opened and closed; and mechanism for opening and closing the molds, for shifting the conveyer, for tilting the ladle, and for opening and closing the valved pipe.

18. In casting apparatus, a primary heating receptacle in which metal is adapted to be melted; a secondary heating receptacle adapted to receive molten metal from the first-named receptacle, and in which the temperature of the molten metal is adapted to be raised; a valved pipe for delivering molten metal from the first-named receptacle to the second; a conveyer; a plurality of molds on the conveyer, and composed of relatively movable parts so that the molds may be opened and closed; and mechanism for shifting the conveyer, for opening and closing the molds, for opening and closing the valved pipe, and for tilting the secondary heating receptacle.

In testimony whereof, I hereunto affix my signature.

ERNEST DISINGER.
